HYDRAULIC PUMP

Benjamin F. Schmidt, Los Angeles, Calif.

Application March 24, 1949, Serial No. 83,268

6 Claims. (Cl. 103—45)

1

This invention relates to a pumping system particularly designed for pumping rotary mud and other slurries.

In general the object of my invention is the provision of a pumping system wherein one or more pumps of the expansible chamber type is or are alternately subjected to superatmospheric and subatmospheric pressure created within a closed working medium circuit including a fluid working medium container, a working medium pump, a combination fluid motor and meter, and an automatic valve actuated by the fluid motor and serving to control the cycle of operation of the expansible chamber type pumps in response to measured quantities of working medium through the closed circuit.

A further object of this invention is the provision of a new and novel closed fluid working medium circuit for alternately reciprocating the diaphragms of two or more diaphragm pumps.

Still another object of this invention is the provision of a new and novel diaphragm type slurry pump.

The invention possesses other advantageous features, some of which, with the foregoing, will be set forth at length in the following description where that form of the invention which has been selected for illustration in the drawings accompanying and forming a part of the present specification is outlined in full. In said drawings, one form of the invention is shown, but it is to be understood that it is not limited to such form, since the invention as set forth in the claims may be embodied in a plurality of forms.

Referring to the drawings:

Fig. 1 is a top plan view of a pumping system embodying the objects of my invention.

Fig. 2 is a section taken on the line 2—2 of Fig. 1, showing the details of construction of the diaphragm pump, the automatic rotary valve for controlling the operating cycle of the pump, and the combination fluid motor and flow meter associated with the rotary valve.

Briefly, the pumping system shown in these figures includes a plurality of identical, symmetrically arranged diaphragm slurry pumps each provided with a pair of check valves for controlling the ingress and egress of the slurry to be pumped and each provided with a working chamber arranged to be subjected alternately to subatmospheric and superatmospheric pressure under the control of a common rotary valve. The automatic valve is in closed circuit with a container for the fluid working medium, with a working medium pump of any well-known type,

2

and with a combined fluid motor and meter having a driving connection with the rotary valve and by which the rotary valve is made to operate in response to metered quantities of the working medium through the system.

More specifically, my pumping system includes a frame generally designated by the reference numeral 1 and on which is symmetrically mounted a plurality of identical diaphragm pumps 2, 3, 4 and 5, each provided with a slurry intake port 6 and with a slurry outlet port 7. Each of the slurry inlet ports 6 is manifolded to a pipe 8 provided with a flange 9 for connecting it to a source of the slurry to be pumped. Similarly, each of the slurry outlet ports 7 is manifolded to a pipe 11 provided with a connecting flange 12.

As best shown in Fig. 2, each of the diaphragm valves 4 includes a valve casing 13 having a dished cap 14 bolted to its lower end. Clamped between the lower end of the valve body 13 and the cap 14 is a perforated, upwardly arched, diaphragm retainer 15 and a rubber diaphragm 16 serving to divide the valve body and its cap into an upper slurry chamber 17 and a lower working medium chamber 18. Formed in the valve body 13 is a slurry intake bore 19 communicating at its upper end with the slurry intake port 6 and at its lower end with the slurry chamber 17. Mounted within the bore 19 intermediate its ends is a valve seat 21 arranged to receive an upwardly closing poppet valve 22. The valve 22 is provided with a central, upwardly extending guide pin 23 receivable in a sleeve 24 formed integral with the valve seat 21. Extending downwardly from the lower face of the valve 22 centrally therewith and as an integral part thereof, is a cylinder 25 telescopically disposed within the vented bore of a boss 26 extending upwardly from the diaphragm retainer 15. Disposed within the cylinder 25 and acting against the lower end of the valve 22 and the upper face of the bore formed in the boss 26, is a spring 27 serving resiliently to urge the valve 22 to its closed position. Communicating with the slurry outlet port 7 is a slurry outlet bore 28 and mounted within this bore is a valve seat 29 in all respects similar to the valve seat 21 with the exception that it faces upwardly rather than downwardly. Operatively associated with the valve seat 29 is a downwardly closing poppet valve 31 identical in all respects to the poppet valve 22, this valve being resiliently urged to its closed position by a spring 32 accommodated within a cylinder 33 formed as an upward extension of the valve 31 and which has telescopic

engagement with a vented bore 34 formed in the lower end of a pin 35. The pin 35 is formed integral with a cap 36 serving to close the upper end of the port 28 and provided with a wrench socket 37 by which it can be readily removed. Disposed between the diaphragm retainer 15 and the diaphragm 16 is a coil spring 38 held in place at its upper end by a pin 39 extending through the diaphragm retainer and seated at its lower end on a wear disc 40 cemented to the diaphragm. Recessed in the inner face of the cap 14 in registration with its inlet and outlet port 41 is a diaphragm guard 42.

During the downward stroke of the diaphragm 16, slurry is drawn through the intake port 6 of the valve and past the poppet valve 22 under the influence of the partial vacuum created as a result of the downward travel of the diaphragm. The slurry which thus fills the chamber 17 above the diaphragm 16 is then forced upwardly by the upward movement of the diaphragm, past the poppet valve 31 and through the slurry outlet port 7 into the pipe 11.

Bolted to each of the ports 41 of the diaphragm pump caps 14 is an inwardly flaring conduit 53 and fastened to the inner ends of each of these conduits by a ring 54 is the cylindrical valve casing 55 of a rotary control valve generally designated by the reference numeral 56. Preferably the rotary valve 56 is symmetrically positioned with respect to each of its associated diaphragm valves 2, 3, 4 and 5, as best shown in Fig. 1, and is mounted on the frame 1.

Journalled in suitable bearings formed in the upper and lower ends of the valve casing 55 and sealed therein in any conventional manner is a shaft 57. Dividing the valve casing 55 intermediate its ends into a pressure chamber 58 and a vacuum chamber 59 is a partition 61 through which the shaft 57 passes and which is sealed therein by packing 62. Keyed to the shaft 57 within the pressure chamber 58 and having a running fit with the inner surface of the casing 55 is a cylindrical valve gate 63 formed with a discharge port 64 arranged to establish communication between the pressure chamber 58 and the inwardly flared conduit 53 during each revolution of the gate 63. Keyed to the shaft 57 within the vacuum compartment 59 is a cylindrical gate 65 provided with a port 66, this port being angularly staggered with respect to the port 64 of the gate 63, and arranged to establish communication between the conduits 53 and the vacuum chamber 59 during each revolution of the shaft 57. As a result of this construction each of the working chambers 18 of each of the four diaphragm valves 2, 3, 4 and 5 is sequentially and alternately subjected to the fluid pressure existing within the pressure chamber 58 during the working stroke of the diaphragms and to the partial vacuum existing within the vacuum chamber 59 during the downward stroke of each of the diaphragms. Keyed to the upper end of the shaft 57 is a sprocket 67 driven by a chain 68 and which serves to rotate the shaft in response to the flow of metered quantities of working medium through the valve 56 as will be presently explained.

Bolted to an elbow 69 provided on the upper end of the valve 56 is a conduit 71 formed at its outer end with an outwardly flared coupling 72. Bolted to the coupling 72 is a combined fluid motor and flow meter generally designated by the reference numeral 73. The fluid motor and flow meter include a generally cylindrical casing 74

formed on one side with a circular bulge 75. Journalled on a vertical axis in opposed bearings formed in the lower and upper walls of the casing 74 is a shaft 76 and keyed to the upper end of this shaft is a sprocket wheel 77 serving to drive the chain 68. Bolted to and within the valve casing 74 is a cylindrical cage 78 eccentrically disposed with respect to the shaft 76 and which snugly fits the casing bulge 75.

Keyed to the shaft 76 concentrically therewith is a cylindrical vane carrier 79 provided with radially extending longitudinal slots for the sliding reception of a plurality of vanes 81. Disposed between the inner end of each of these vanes and the shaft 76 is a spring 82 serving resiliently to urge each of its associated vanes outwardly so that the outer end thereof has sliding engagement with the eccentric inner surface of the cage 78. As a result of this construction, oil, water or other fluid working medium entering the inlet 84 of the casing 74 exerts a pressure on the vanes 81 and due to the eccentric disposition of these vanes and their associated shaft 76 they will be caused to rotate in clockwise direction as viewed in Fig. 1. Furthermore, since adjacent pairs of vanes form pockets each of a predetermined maximum capacity which are filled with the working medium during the rotation of the vanes, the shaft rotates at a rate correlated to the flow of metered quantities of working medium through the casing 74 and through the rotary valve 56. It will therefore be seen that the automatic valve 56 operates in response to the flow of metered quantities of working medium through the system, and that consequently the cycle of operation of each of the four diaphragm pumps 2, 3, 4 and 5 is likewise controlled by the flow of metered quantities of working medium through the system.

Bolted to an elbow 85 provided on the lower end of the automatic valve 56 and communicating with the vacuum compartment 59 thereof is a conduit 86. The conduit 86 communicates with a closed sump or fluid working medium container 87 which in turn communicates through a conduit 88 with the low pressure side of a conventional working medium pump 89. The high pressure side of the pump 89 communicates through a conduit 91 with the intake 84 of the fluid motor and flow meter 73.

From the above description it will be seen that I have provided a pumping system wherein the cycle of operation of a plurality of expansible chamber type slurry pumps such as a diaphragm pump, is under the control of a common rotary valve, this valve being in closed circuit with a working medium container, a working medium pump and a combined fluid motor and meter serving to actuate the rotor of the control valve in response to metered quantities of working medium flowing through the system and which in turn serves to permit the pump diaphragms to be actuated in response to the predetermined movement of a closed column of working medium.

I claim:

1. A pumping system of the character described comprising: a first pump of the expansible chamber type including a pumping chamber and a working chamber and a pumping element between them; a second pump in closed circuit with a fluid working medium container; a control valve disposed in said circuit, said valve being connected to said working chamber and arranged alternately to establish communication between said chamber and the low and high pressure

sides of said second pump; a fluid motor disposed in said circuit between the high pressure side of said second pump and said control valve; and means for actuating said valve in response to the movement of said motor.

2. A pumping system of the character described comprising: a first pump of the diaphragm type including a working chamber and a pumping chamber and a diaphragm pumping element between them, said pumping chamber being provided with check valve controlled inlets and outlets; a second pump in closed circuit with a fluid working medium container; a control valve disposed in said circuit, said valve being connected to said working chamber and arranged alternately to establish communication between said working chamber and the low and high pressure sides of said second pump; a fluid motor disposed in said circuit between the high pressure side of said second pump and said control valve; and means responsive to the movement of said motor for actuating said valve.

3. A pumping system of the character described comprising: a plurality of pumps of the expansible chamber type each including a pumping chamber and a working chamber and a pumping element between them; another pump in closed circuit with a fluid working medium container; a valve disposed in said circuit, said valve being manifolded to said working chambers and arranged alternately to establish communication between each of said chambers and the low and high pressure sides of said other pump; a fluid motor disposed in said circuit between the high pressure side of said other pump and said valve; and means for actuating said valve in response to the movement of said motor.

4. A pumping system of the character described comprising: a pump of the expansible chamber type including a working chamber and a pumping element therein; a rotary valve including a cylindrical valve casing provided with a high pressure chamber and a low pressure chamber; a conduit communicating between said working chamber and with said high pressure chamber through a discharge port formed in said casing and with said low pressure chamber through an intake port formed in said casing; and rotary valve gates

mounted in said cylindrical casing, said valve gates being arranged to successively open and close said discharge and intake ports.

5. A pumping system of the character described comprising: a pump of the expansible chamber type including a working chamber and a pumping element therein; a cylindrical valve casing divided by a partition intermediate its ends into a high pressure chamber and a low pressure chamber; a first conduit communicating with said working chamber and said high and low pressure chambers respectively through outlet and inlet ports formed in said valve casing; rotary valve gates mounted in said valve casing arranged to successively open and close said outlet and inlet ports; a working medium pump having its low pressure side in communication with said low pressure chamber and its high pressure side in communication with said high pressure chamber; and means for actuating said rotary valve gates in response to the flow of working medium from the high pressure side of said working medium pump.

6. A pumping system of the character described comprising a pump of the expansible chamber type including a working chamber and a pumping element therein, a closed liquid working medium circuit including a working medium pump, a rotary control valve communicating with said circuit and with said working chamber for alternately establishing, upon rotation thereof, communication between said chamber and the low and high pressure sides of said working medium pump, and a fluid motor disposed in said circuit and connected to said valve for rotating the same.
